UNITED STATES PATENT OFFICE.

MARQUIS D. L. HARTLEY, OF DEHESA, CALIFORNIA.

DESIGN FOR A FRUIT-PICKER.

SPECIFICATION forming part of Design No. 32,489, dated April 10, 1900.

Application filed March 7, 1900. Serial No. 7,739. Term of patent 7 years.

To all whom it may concern:

Be it known that I, MARQUIS D. L. HARTLEY, a citizen of the United States, and a resident of Dehesa, in the county of San Diego and 5 State of California, have invented and produced a new and original Design for a Fruit-Picker, of which the following is a full, clear, and exact description.

Reference is to be had to the accompanying 10 drawings, forming a part of this specification, in which similar characters of reference indicate corresponding parts in all the figures.

Figure 1 is a perspective view of a fruit-picker embodying my design. Fig. 2 is a longitudinal section on the line 2 2 of Fig. 3, and 15 Fig. 3 is a cross-section on the line 3 3 of Fig. 2.

The leading feature of my design consists 20 in the fruit-picker having an elongated body concaved on one side transversely and also longitudinally, as at A, and having an arched cross-band A' at about the center on the same side, while on the other side the body has a sharp longitudinal rib A². This rib, as shown, 25 is of gradually-reduced width from the center toward the ends, while the body has substantially the same width throughout, and the longitudinal edges A³ of the body connect under gradual transition with the round end edges A⁴. The curvature of the band A' is such that the height of the space inclosed between said band and the concave surface A of the body is less than the width of said space, as shown particularly in Fig. 3. As will be seen in Figs. 1 and 3, the convex edge of the rib A² is spaced from the body A, which has 35 an opening A⁵ on that side from which the rib projects.

Having thus described my invention, I claim as new and desire to secure by Letters Patent—

The design for a fruit-picker as herein 40 shown and described.

In testimony whereof I have signed my name to this specification in the presence of two subscribing witnesses.

MARQUIS D. L. HARTLEY.
